CLAIM

I claim the ornamental design for the steering wheel lock and air bag anti-theft device, as shown.

DESCRIPTION

FIG. 1 is a perspective top view of the steering wheel lock and air bag anti-theft device.

FIG. 2 is a top view of the device shown in FIG. 1.

FIG. 3 is a front elevational view of the device shown in FIG. 1.

FIG. 4 is a rear elevational view of the device shown in FIG. 1.

FIG. 5 is a right side view of the device shown in FIG. 1.

FIG. 6 is a left side view of the device shown in FIG. 1; and,

FIG. 7 is a bottom view of the device shown in FIG. 1.

1 Claim, 4 Drawing Sheets

FIG. 1

FIG. 7
